UNITED STATES PATENT OFFICE.

LEONARD A. YOUNG, OF HIGHLAND PARK, MICHIGAN.

SPRING-SEAT CONSTRUCTION.

Application filed June 21, 1921. Serial No. 479,382.

To all whom it may concern:

Be it known that I, LEONARD A. YOUNG, a citizen of the United States, residing at Highland Park, in the county of Wayne and 5 State of Michigan, have invented certain new and useful Improvements in Spring-Seat Constructions, of which the following is a specification.

In the use of spring seat constructions 10 wherein upright body springs, connected in various ways, support upholstery, it is found that if springs of different periods of vibration are employed it prevents the rebound which occurs where the springs are all of the 15 same elasticity. It is frequently desirable to obtain the result of compounding the springs by placing springs one above the other, the upper ones usually being more pliable than the lower. Because of their helical form, it is difficult to secure the base of 20 one spring to the top of the spring on which it rests and so it is quite common to interpose a deck or yielding platform between the lower springs and the upper ones, but 25 this impairs the resiliency of the cushion as the load is transmitted from each of the upper springs to all the base springs, in a measure, through this intermediate platform.

This invention relates to spring seat constructions 30 wherein the body springs are compounded or built up so as to provide the desired elasticity of the freedom from rebound and at the same time preserve the individual action of each body spring, a feature which is not obtainable by the use of 35 the intermediate deck, this result being obtained by the use of individual deck plates which unite the end coils of a pair of super- 40 posed springs and also form a seat for the upper one of each pair.

The invention consists in the matters hereinafter set forth and more particularly pointed out in the appended claims.

In the drawing Fig. I is a fragmentary 45 plan view of a spring seat construction embodying the features of my invention, the upholstery being omitted for convenience in illustration.

Fig. II is an enlarged detail vertical section 50 on a line corresponding to line 2—2 of Figs. I and III, looking in the direction of the arrows showing details of my improved spring connector.

Fig. III is a detail view showing details 55 of my improved cross stay.

In the drawing similar numerals of ref-

erence refer to similar parts throughout all the views.

Referring to the drawing, I provide a suitable supporting base, which, in the structure illustrated, comprises a bottom rim 1 and cross strips 2. However, as the structure of the base forms no part of this invention, the details thereof are not further illustrated or described. I preferably provide a top border rim 3.

The structure illustrated is designed for 60 spring seats such as automobile cushion seats and it will be understood that in practice 65 the spring construction is suitably upholstered.

I provide a set of bottom springs 4 which are suitably supported on the base and a set of top springs 5, the top springs being 70 more resilient than the bottom springs, thus 75 providing a soft upper deck for the cushion and a stiffer bottom deck to resist the heavier strains or loads. These springs are disposed in superimposed relation and in axial alignment as shown in Fig. III.

The springs of the upper and lower sets 80 are connected by the connectors 6 which have oppositely facing channels formed therein 85 with a downwardly facing channel 7 engaging the upper coils 8 of the lower springs, while the upwardly facing channels 9 are clamped upon the lower coils 10 of the upper set of springs. These connectors in the 90 embodiment illustrated are formed of sheet metal plates, the channels being concentric and facing oppositely as illustrated.

In the structure illustrated I provide one or more cross bases 11 which have laterally turned ends 12 engaged in the channels 13 95 of the U-shaped tie members 14 which are secured by the rivets 15 to the connectors of adjacent springs. This brace serves to assist in supporting the structure in upright position and supports the springs against 100 tilting movement.

As a result of this construction, a spring seat is obtained which has the desired pliancy or softness in the upper portion, due to the upper body springs which may be very light, the resistance to severe shock afforded by the lower stationary body springs, and the resistance to lateral displacement provided for by the cross stays. Another feature is the freedom of the action of each body spring which may be compressed independently of any adjacent spring. Another feature is the use of the spring sup-

ports between the upper and lower sections of each body spring, which, because they are perforated, prevent the end coils of the springs from working loose and turning into each other, a common fault where clips alone are used to hold the end coils of springs of this type.

Obviously changes in the detail of construction may be made without departing 10 from the spirit of the invention and I do not care to limit myself to any particular form or arrangement of parts.

I claim as my invention:

1. In a spring structure a compound 15 spring consisting of superimposed springs, connectors therefor comprising sheet metal plates having concentric oppositely facing channels therein, the downwardly facing channel being engaged and clamped upon 20 the top coils of the lower springs and the upwardly facing channels engaging with and clamped upon the bottom coils of the

upper springs, tie members of U-cross section secured to the connectors of adjacent springs, and braces disposed with their ends 25 engaging the channels of said tie members.

2. In a spring structure, a compound spring consisting of superimposed springs, connectors therefor comprising sheet metal plates having concentric oppositely facing 30 channels therein, the downwardly facing channel being engaged and clamped upon the top coils of the lower springs and the upwardly facing channels engaging with and clamped upon the bottom coils of the upper 35 springs.

3. A spring seat structure comprising superimposed springs, connecting members therefor formed of sheet metal and having oppositely facing channels, the end coils of 40 the springs being engaged in said channels.

In testimony whereof I affix my signature.

LEONARD A. YOUNG.
